RAILWAY TRUCK FRAME

Rudolf R. Schubert, Greensburg, Pa., assignor to
 Greensburg Machine Company, Greensburg,
 Pa., a corporation of Pennsylvania

Application November 26, 1946, Serial No. 712,376

6 Claims. (Cl. 105—182)

1

This invention relates to a railway-truck frame. Primarily considered, this invention concerns itself with improvements in the frame of a railway-truck having its most clearly indicated utility in mines and industrial plants. Such truck in itself is adapted to incorporation either in a railway vehicle which is self-propelled or a vehicle which receives locomotion from another vehicle which serves as a locomotive. In general my invention follows the line of construction for a railway-truck disclosed in the application of Arthur L. Lee, Serial No. 539,947, while presenting improvements over that structure.

Briefly stated, a railway-truck assembly in which my invention is incorporated comprises the combination of a side frame and longitudinally spaced wheel-carrying axles, with a beam extended longitudinally of the frame and having swinging movement in a vertical plane with respect to said frame at a deflection point intermediate the axles, and yielding load-transmitting elements spaced longitudinally from said deflection point on both sides thereof and between the said beam and the said frame in stabilizing relation with the frame to transmit load to the frame at longitudinally spaced points. Brakes and brake-operating connections are carried by the said beam, which rides on the vehicle axles and can move vertically at either end thereof with vertical movement of the wheels and axles. If the vehicle is to be self-propelled, the transmission by which power is delivered to the wheels desirably is also carried by the beam, so that the transmission also adjusts itself automatically to vertical movement of the vehicle wheels.

My invention resides in improvements in a railway-truck constructed as above outlined by which the yielding load-transmitting elements which act between the wheels with their associated beam and the frame of the vehicle are so placed that they transmit loads axially of their structure, without tendency toward angular distortion in performance of their function; by which the said yielding load-transmitting means are housed and supported in a manner to increase their effectiveness and prolong their usefulness; and in which the organization of the vehicle is such that the wheels of the vehicle may, without alternation in the structural design of the vehicle, be placed either inside or outside the frame elements in conformity with the width of the vehicle or the gage of the track on which it is to run.

In the embodiment of my invention shown in the accompanying drawings:

Fig. I is a plan view of a railway-truck in ac-

2

cordance with my invention, organized for self-propulsion.

Fig. II is a side elevation of the railway-truck assembly shown in Fig. I.

Fig. III is a view on a larger scale showing the main side frame of the assembly partially in vertical section and partially in side elevation.

Fig. IV is a bottom plan view of the side frame shown in Fig. III.

Fig. V is a side elevation of the swinging, or oscillating, beam of the railway-truck frame assembly, on the same scale as Figs. III and IV but showing the beam slightly broken away intermediate its length.

Fig. VI is an end elevation of the beam shown in Fig. V.

Fig. VII is a fragmentary side elevation of a side frame, parts being removed and parts being shown in section, taken on the broken line VII—

20 VII of Fig. I, and showing a side frame throughout the greater proportion of its length, together with the elements associated therewith.

Fig. VIII is a vertical sectional view through a pivot connection between side frame and beam, taken in the plane of the section line VIII—VIII of Fig. VII.

Fig. IX is a greatly enlarged fragmentary side elevation of the side frame, taken in a region midway of its length.

Fig. X is a vertical sectional view taken in the plane of the section line X—X of Fig. IX.

Fig. XI is a vertical sectional view through the brake-operating connection to the beam, taken in the plane of the section line XI—XI of Fig. VII.

Fig. XII is a detail plan view, showing the brakes and brake-operating connections of the railway-truck in which the frame structure of my invention is incorporated, illustrating the attachment of the brakes to the beam of the frame structure and illustrating the relation of the brake assembly to the frame and wheels of the truck.

Fig. XIII is a detail side elevation of the elements shown in plan in Fig. XII and illustrating the relation of a brake assembly to an oscillating beam and wheels of the truck.

Referring first to Figs. I and II of the drawings for the general arrangement of the railway truck in which the frame structure of my invention is incorporated, reference numerals 1 and 2 designate wheel-carrying axles equipped with track-engaging wheels 3. End structures 4 and 5 provide a platform for the operator of the vehicle (shown as equipped for self-propulsion), control means, space or support for mounting a

motor, and support for coupling and buffering elements. Such end structures are rigidly secured to a pair of laterally spaced side frame elements 6, which form the primary rigid structure of the truck.

Referring now particularly to Figs. III to IX inclusive of the drawings, those figures show in detail the side frame and beam elements which together form the frame structure of the truck and mounting means for the yielding load-transmitting elements associated with them.

Each of the side frames 6, as shown in Figs. III and IV comprises two parallel plates 6a and 6b which are spaced laterally from each other to leave a beam-receiving space 7 between them. From their lower edges both plates of the side frame are cut away upwardly to provide aligned windows 8 arranged to straddle journal boxes 9 (see Fig. VII), have aligned pivot holes 10, and have aligned windows 11 and 12 for the entry of brake-operating supports and connections to the beam between the plates. At both ends of the side frame there is a tubular housing 13 for a coil spring with a seat and spring positioning core 14 in the upper region of each of the housings. It will be noted that each of the tubular spring housings 13 is axially aligned with the beam-receiving space 7 between the plates of the side frame and has in its lower region a slot 13a communicating with the space 7 between the walls of the side frame. Midway their length both plates 6a and 6b of the side frame are cut away below flange 15 to provide a window 16 for mounting a transmission hanger on the oscillating beam. A second window 17 is provided to accommodate a brake-operating bar. It will be noted that Fig. III is in measure incomplete, inasmuch as it omits the welded flange shown in Figs. VII, VIII and IX.

The oscillating beam 18, shown individually in Figs. V and VI of the drawings, consists primarily of a single plate adapted for reception between the plates 6a and 6b of the side frame. Extended upwardly from its lower edge are windows 19 arranged in assembly to embrace and slidably engage journal boxes 9 and to receive load from and transmit it to the axles 1 and 2. Midway of its length the beam has a cut-out window 20 arranged to embrace and slidably engage a pivot block 21 (see Figs. VII to X inclusive), and is provided with holes 22 for the attachment of brake hangers. At its ends the plate carries spring platforms 23 having thereon upstanding spring-positioning cores 24. Platforms 23 are joined to the body of beam 18 by means of a narrow neck portion 23a to permit the platforms and spring-positioning cores 24 to enter spring housings 13 by way of slots 13a.

In assembly beam 18 lies in the space 7 between the plates of side frame 6 with pivot block 21 slidably engaged in its cut-out window 20. In pivot block 21 there is a pintle 25, which is fixed to side frame 6 and about which the pivot block and beam may turn. At each end of the beam a spring platform and spring-positioning core lies in the lower region of one of the spring housings 13 of the side frame, so that the coil spring 26 stands vertically between the two elements in position to be compressed by their relative movement. The assembly load thus is transmitted to the side frame through yielding elements, which are shown as the coil springs 26, that load being initially assumed by the beam 18 which rests directly on the journal boxes 9. The points of load-transmission provided at the coil springs

are spaced substantially from the pivot point of the beam and that pivot carries no vertical load. Normally, turning movement of the beam in a vertical plane because of track inequalities and like causes is almost imperceptible, being yieldingly absorbed by the coil springs 26.

If there should be an abrupt vertical shock, such as might occur because of a depressed region of track, injury to the frame assembly is avoided by the provision for some relative vertical movement between beam 18 and side frame 6. It will be observed that, to permit this latter movement, the vertical dimension of window 20 in the beam is sufficient to provide spaces 20a and to permit the side frame 6, and pivot block 21 with it, to move vertically relatively to the beam.

It will be noted that in this assembly, which is identical on both sides of the truck, the beam 18 is in fixed relation with the axles and is centered laterally with respect to journal boxes 9. Thus if the track be self-propelled, the beam serves to transmit tractive effort to the side frame, through pivot block 21. The double wall of the side frame, with the oscillating beam in the space between the walls, give an accurate alignment between the vertical plane of the beam and the axles of the coil springs. This structure accurately centers load-transmission. With respect to the brake mountings and brake-operating connections, both these assemblies also are identical on both sides of the truck, and are carried on both sides by the beams which maintain a fixed relation to the axles and wheels. As shown, the brakes are hand-operated, being actuated by means of an operating wheel 27, operating rod 28 and a cross bar 29 which latter lies in the windows 17 in both the side frames and above the oscillating beams. The brakes and their proximate elements comprise brake shoes 30 and 31, which are mounted on hangers 32 and 33 respectively. These hangers are secured, on each side of the truck, to the beam 18 by means of attachment pins 34 which pass through windows 11 and 12 in one of the walls of the side frame and pivotally engage in the holes 22 of the beam. As shown, both the wheels of the truck and the brake system are mounted inside the side frames, so that pins 34 reach the beam by way of the windows through the inner wall 6b of the side frame.

Brake shoes 30 and 31 are operatively connected with actuating bar 29, by means of a brake-operating lever 35 which is pivoted at 36 to the actuating bar 35a and which is pivoted at 37 to hanger 32 of brake shoe 30. Brake lever 35 also is pivotally engaged at 38 with a drag link 39, which has pivoted engagement with hanger 33 of brake shoe 31 at a pivot point 40.

The brake shoes are thus carried directly by oscillating beam 18, and they and their operating connections are free of engagement with the side frame of the truck. These operating connections derive movement from bar 29, which lies free in windows 17 of the side frame, and operating rod 28 has universal joints 41 and 42, so that movement of the brake system with the beam is not inhibited by the mounting of that rod between the side frame elements of the truck. Because the brake system thus is movable with the wheels of the truck in fixed relation thereto, the brake shoes may lie very close to the treads of the wheels, and movement of the brake shoes is minimized.

It will be observed that the organization of the railway-truck frame is such as to produce centered alignment in load transmission to the frame,

together with extended guiding structure for the oscillating beam during its swinging movement in a vertical plane. The frame thus is relieved to a maximum of torsional stresses as are also the load-transmitting springs; and the frame assembly has great strength without substantial increase in weight or in structural complexity.

I claim as my invention:

1. A railway truck assembly having two parallel spaced longitudinally extended side frame elements, the structure at each side of the truck including a side frame element comprising two vertically and longitudinally extended walls laterally spaced to provide a housing space therebetween, wheel-carrying axles spaced longitudinally of the said side frame elements, a longitudinally and vertically extended beam housed between the walls of the side frame and having fixed longitudinal relation with the said axles, a vertically unloaded pivot block mounted for vertical sliding movement between the walls of the said side frame intermediate the said axles and a horizontal pivot pin passed through the said pivot block, one of said elements comprising the said block and pin being mounted with the walls of the side frame and the other thereof mounted with the said beam to provide relative vertical movement between said beam and said side frame and swinging movement of said beam, and yielding load-transmitting elements spaced longitudinally from the deflection point provided by said pivot pin on both sides thereof and vertically between the said beam and the said side frame.

2. A railway truck assembly having two parallel spaced longitudinally extended side frame elements, the structure at each side of the truck including a side frame element comprising two vertically and longitudinally extended walls laterally spaced to provide a housing space therebetween, wheel-carrying axles spaced longitudinally of the said side frame elements, a longitudinally and vertically extended beam housed between the walls of the side frame and having fixed longitudinal relation with the said axles, a vertically unloaded pivot block mounted for vertical sliding movement between the walls of the said side frame intermediate the said axles and a horizontal pivot pin passed through said pivot block, one of the said elements comprising the said block and pin being mounted with the wall of the side frame and the other thereof mounted with the said beam to provide relative vertical movement between said beam and said side frame and swinging movement of said beam, yielding load-transmitting elements spaced longitudinally from the deflection point provided by said pivot pin on both sides thereof and vertically between the said beam and the said side frame, openings in a wall of the side frame and brake-mounting structure extended through said openings and engaged with the beam, and a brake system supported from the beam by said brake-mounting structure free of engagement with the side frame in fixed relation with said axles and wheels carried thereby.

3. A railway truck assembly having two parallel spaced longitudinally extended side frame elements, the structure at each side of the truck including a side frame element comprising two vertically and longitudinally extended walls laterally spaced to provide a housing space therebetween, wheel-carrying axles spaced longitudinally of the said side frame elements, a longitudinally and vertically extended beam housed be-

tween the walls of the side frame and having fixed longitudinal relation with the said axles, a vertically unloaded pivot block between the walls of the said side frame intermediate the said axles and vertically slidably in said beam and a horizontal pivot pin mounted in said side frame and passed through the said pivot block, to provide relative vertical movement between said beam and said side frame and swinging movement of said beam, and yielding load-transmitting elements spaced longitudinally from the deflection point provided by said pivot pin on both sides thereof and vertically between the said beam and the said side frame.

4. A railway truck assembly having two parallel spaced longitudinally extended side frame elements, the structure at each side of the truck including a side frame element comprising two vertically and longitudinally extended walls laterally spaced to provide a housing space therebetween, wheel-carrying axles spaced longitudinally of the said side frame elements, a longitudinally and vertically extended beam housed between the walls of the side frame and having fixed longitudinal relation with the said axles, a vertically unloaded pivot block between the walls of the said side frame intermediate the said axles and vertically slidably in said beam and a horizontal pivot pin mounted in said frame and passed through said pivot block, to provide relative vertical movement between said beam and said side frame and swinging movement of said beam, yielding load-transmitting elements spaced longitudinally from the deflection point provided by said pivot pin on both sides thereof and vertically between the said beam and the said side frame, openings in a wall of the side frame and brake-mounting structure extended through said openings and engaged with the beam, and a brake system supported from the beam by said brake-mounting structure free of engagement with the side frame.

5. A railway truck assembly having two parallel spaced longitudinally extended side frame elements, the structure at each side of the truck including a side frame element comprising two vertically and longitudinally extended walls laterally spaced to provide a housing space therebetween, wheel-carrying axles spaced longitudinally of the said side frame elements, a longitudinally and vertically extended beam housed between the walls of the side frame and having fixed longitudinal relation with the said axles, a vertically unloaded pivot block mounted for vertical sliding movement between the walls of the said side frame intermediate the said axles and a horizontal pivot pin passed through the said pivot block, one of elements comprising the said block and pin being mounted with the walls of the side frame and the other thereof mounted with the said beam to provide relative vertical movement between said beam and said side frame and swinging movement of said beam, tubular housings fixed adjacent the ends of said side frame arranged symmetrically with respect to the walls thereof and in alignment with the said beam, extensions at the ends of the beam within the lower regions of the said tubular housings of the side frame and load-transmitting springs in said tubular housings and bearing against said extensions of said beam to transmit load yieldingly to said side frame adjacent the ends of the beam.

6. A railway truck assembly having two parallel spaced longitudinally extended side frame ele-

ments; the structure at each side of the truck including a side frame element comprising two vertically and longitudinally extended walls laterally spaced to provide a housing space therebetween, wheel-carrying axles spaced longitudinally of the said side frame elements, a longitudinally and vertically extended beam housed between the walls of the side frame and having fixed longitudinal relation with the said axles, a vertically unloaded pivot block between the walls of the said side frame intermediate the said axles and vertically slidable in said beam and a horizontal pivot pin mounted in said side frame and passed through the said pivot block, to provide relative vertical movement between said beam and said side frame and swinging movement of said beam, tubular housings fixed adjacent the ends of said side frame arranged symmetrically with respect to the walls thereof and in alignment with the said beam, extensions at the ends of the beam

10

5

within the lower regions of the said tubular housings of the side frame and load-transmitting springs in said tubular housings and bearing against said extensions of said beam to transmit load yieldingly to said side frame adjacent the ends of the beam.
